(57) CLAIM

The ornamental design for a hand cart, as shown and described.

DESCRIPTION

FIG. 1 is a front, right and bottom perspective view of a hand cart, showing my new design;

FIG. 2 is a rear, left and top perspective view thereof;

FIG. 3 is a front, right and bottom perspective view of the hand cart in a use state;

FIG. 4 is a front, right and bottom perspective view of the hand cart in a detached state;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is an enlarged view of portion 11 shown in FIG. 1; and,

FIG. 12 is an enlarged view of portion 12 shown in FIG. 1. The dot-dash broken lines depict the boundaries of the enlargements that form no part of the claimed design.

1 Claim, 12 Drawing Sheets
